Primary Examiner — Cathron Brooks*Assistant Examiner* — Catherine Posthauer(74) *Attorney, Agent, or Firm* — Knobbe Martens Olson & Bear, LLP(57) **CLAIM**

The ornamental design for an umbrella hub, as shown and described.

DESCRIPTION

FIG. 1 is a perspective view of the umbrella hub, shown with environmental structure;

FIG. 2 is another perspective view of the umbrella hub;

FIG. 3 is a front or rear view of the umbrella hub;

FIG. 4 is a right or left side view of the umbrella hub;

FIG. 5 is a top view of the umbrella hub; and,

FIG. 6 is a bottom view of the umbrella hub.

The broken lines shown indicate environment and portions of the umbrella hub and form no part of the claimed design.

1 Claim, 4 Drawing Sheets# US D731,166 S
